UNITED STATES PATENT OFFICE.

FRED J. SCHULTZ AND HERMAN M. SCHULTZ, OF NORTH COLLINS, NEW YORK.

GOVERNOR FOR CARBURETER-THROTTLES.

1,123,935.

Specification of Letters Patent.

Patented Jan. 5, 1915.

Application filed May 13, 1914. Serial No. 833,324.

To all whom it may concern:

Be it known that we, FRED J. SCHULTZ and HERMAN M. SCHULTZ, citizens of the United States, residing at North Collins, in the county of Erie, State of New York, have invented certain new and useful Improvements in Governors for Carbureter-Throttles; and we do hereby declare the following to be a full, clear, and exact description of the invention, such as will enable others skilled in the art to which it appertains to make and use the same.

This invention relates to governors for carbureter throttles.

The object of the invention resides in the provision of a device of the type named which as the speed of the engine increases will move the throttle toward closed position and toward open position as the speed of the engine decreases; in other words the device is designed to automatically reduce the supply of explosive mixture as the speed of the engine increases and automatically increase the supply of said mixture as the speed of the engine decreases.

A further object of the invention resides in the provision of a device of the character named which will be simple in construction, efficient in use and which may be readily associated with an explosive engine of ordinary construction.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a view in elevation of a fragment of an explosive engine showing the invention applied; Fig. 2, a plan view of what is shown in Fig. 1; Fig. 3, a view in elevation of the device detached and on an enlarged scale the casing of the device being removed; Fig. 4, a plan view of what is shown in Fig. 3; Fig. 5, a longitudinal section of what is shown in Fig. 3 with the casing in place; and Fig. 6, an end view of the device.

Referring to the drawings 10 indicates an explosive engine, 11 the cam shaft thereof and 12 the carbureter associated with

the engine. This carbureter 12 includes the usual throttle valve having a stem 13 provided with an operating arm 14.

The improved governing device is shown as comprising a base 15 one end of which terminates in an upwardly directed portion 15' having a vertical passage 16 therein opening through the upper edge of the portion 15'. The lower end of the passage 16 communicates with a slot 17 formed in the portion 15' and having slidably mounted therein a bearing 18 for a purpose that will presently appear. Rotatably mounted in the base 15 is a shaft 19 which has fixed on the upper end thereof above the base 15 a friction wheel 20. Fixed on the lower end of the shaft 19 is a beveled gear 21 which meshes with a beveled gear 22 fixed upon the cam shaft 11. Rising from the base 15 is a bearing 23 which has journaled therein a shaft 24. The end of the shaft 24 adjacent the friction wheel 20 is connected to one end of a tubular shaft 25 by a universal joint 26, the other end of said tubular shaft 25 being journaled in the bearing 18. The shaft 25 is provided with oppositely disposed longitudinal slots 27 and slidably mounted on said shaft is a sleeve 28 upon the periphery of which is fixed a friction wheel 29 adapted to coöperate with the friction wheel 20 as will be obvious.

Slidably mounted in the bore of the shaft 25 is a shaft 30 the inner end of which carries a transverse pin 31 engaged through the slots 27 and into the sleeve 28 whereby longitudinal movement of the shaft 30 will effect movement of the sleeve 28 and wheel 29 to adjust the latter toward and away from the center of the wheel 20 and whereby the rotation of the shaft 24 and 25 may be varied while the rotation of the shaft 11 remains constant.

Mounted in the passage 16 is a spring 32 which bears against the bearing 18 and forces the friction wheel 29 into engagement with the friction wheel 20. The tension of the spring 22 may be varied through the medium of a nut 33 threaded in the upper end of the passage 16 as will be obvious. Swiveled on the outer end of the shaft 30 is a bracket 34 including spaced ears 35. Pivotally mounted on the portion 15' of the base and projecting outwardly in substantially a horizontal plane is a forked bracket 36 between the arms of which is pivotally mounted a lever 37, one end of which is

pivots secured between the ears 35 while the other end thereof is pivotally connected to a rod 38 which extends to the steering wheel of an automobile where it is suitably connected with an operating lever. By moving the rod 38 longitudinally it will be obvious that the friction wheel 29 can be moved toward and away from the center of the friction wheel 20. Mounted upon the base 15 is a base bearing 39 and journaled in this bearing is the lower end of a tubular shaft 40. The upper end of the shaft 40 is journaled in the inclosing casing 41 of the device. The upper end of the shaft 40 is provided with oppositely disposed longitudinal slots 42 and pivoted in the upper end of each slot 42 is an arm 43 which carries at its free end a weighted portion 44. Slidably mounted in the bore of the shaft 40 is a rod 45 the upper end of which is connected to the arms 43 by means of links 46. The lower end of the rod 45 has swiveled thereon a bracket 47 for a purpose that will presently appear. The base bearing 39 is provided at its lower end with an opening 48 through which extends a curved lever 49, said lever being pivoted to the base bearing between the walls of said opening. The inner end of the lever 49 is pivotally connected to the bracket 47 while the outer end of said lever is connected to the operating arm 13 of the throttle valve of the carbureter by means of a link 50.

When the engine is started the throttle valve of the carbureter is fully open. As the engine picks up speed the free ends of the arms 43 will move out under the influence of centrifugal force and lift the rod 45. This movement of the rod 45 will in turn pivot the lever 49 which latter through the medium of the link 50 will rotate the throttle valve of the carbureter toward closed position. In this manner the device will serve to automatically control the supply of explosive mixture to the engine.

It will be noted that the shaft 40 has fixed thereon a beveled gear 51 which meshes with a beveled gear 52 fixed on the shaft 24 and whereby the rotation of the shaft 24 will effect a rotation of the shaft 40. 50

What is claimed is:—

In a device of the class described, the combination of a base, a shaft rotatably mounted in the base at right angles to the latter and adapted to be operatively connected to a rotating portion of an explosive engine, a friction wheel fixed on said shaft, a second shaft rotatably mounted on the base at right angles to the first named shaft, a friction wheel nonrotatably and slidably mounted on the second named shaft and engaging the friction wheel on the first named shaft, means for sliding the friction wheel on the second named shaft toward and away from the center of the friction wheel on the first named shaft to vary the speed of rotation of the second named shaft, a vertical tubular shaft rotatably mounted on the base, connections between the vertical tubular shaft and the second named shaft for effecting the rotation of the former, a rod slidably mounted in the tubular shaft, a lever pivoted on the base having one end pivotally connected to the lower end of said rod and its other end adapted for connection to the throttle valve of a carbureter whereby the swinging of said lever will operate the valve to opened and closed positions, and centrifugally operated means for lifting said rod as the speed of rotation of the tubular shaft increases to move the lever in a direction to close the throttle valve. 80 75

In testimony whereof, we affix our signatures, in the presence of two witnesses.

FRED J. SCHULTZ.
HERMAN M. SCHULTZ.
